UNITED STATES PATENT OFFICE.

PERRY J. WALLER, OF LOS ANGELES, CALIFORNIA.

PUMP-PISTON.

SPECIFICATION forming part of Letters Patent No. 770,513, dated September 20, 1904.

Application filed December 21, 1903. Serial No. 186,113. (No model.)

To all whom it may concern:

Be it known that I, PERRY J. WALLER, a citizen of the United States, residing at Los Angeles, in the county of Los Angeles and State 5 of California, have invented new and useful Improvements in Pump-Pistons, of which the following is a specification.

My invention relates to a piston for a plunger-pump; and the object thereof is to produce a piston in which all danger of the valve sticking and not seating shall be eliminated when the piston is in operation. I accomplish this object by the mechanism described herein and illustrated in the accompanying drawings, in which—

Figure 1 is a central vertical section of my piston disconnected from the operating mechanism, showing the valve in its elevating position for the passage of water therethrough. Fig. 2 is a central vertical section of my piston, showing the valve closed. Fig. 3 is a cross-section on the line 3 3 of Fig. 1 looking in the direction of the arrow.

In the drawings, A is the piston-stem, to the lower end of which is secured the valve-seat B. In the upper end of this stem is a socket C for the reception of the plunger-rod, (not shown,) by means of which the piston is operated. Near the socket the piston-stem is provided with a shoulder A', to the bottom of which are secured lugs A'', which are preferably cast integral with the shoulder and stem. These lugs serve as a stop to limit the upward movement of the valve D, which is loosely and slidably mounted upon the piston-stem intermediate the valve-seat and the shoulder. Other means may be used to limit the movement of the valve. In the valve and surrounding the piston-stem are a plurality of channels E, which provide waterways for the passage of the water up through the valve and between the valve and stem into the space above the valve and below the shoulder, from which space the water passes out above the valve between the lugs on the shoulder. To the lower face of the valve I preferably secure a gasket F, of sole-leather; but the same may be of any desired material. If desired, the gasket may be omitted by facing the valve. When the

valve rests upon the valve-seat, this gasket 50 covers the openings G in the valve-seat, so that no liquid may flow back through the valve-seat. In the operation of my piston it is reciprocated in the pump-barrel (not shown) in the usual manner, the valve-seat closely fitting the sides of the barrel. As the piston is pushed downward in the pump-barrel the liquid therein forces the valve to the elevated position. (Shown in Fig. 1.) A part of the liquid flows around the outside of the valve and 60 a part flows through the channels E and thence out between the lugs A'' into the barrel above the valve. The flow of liquid through the channels E prevents any sand or other obstructions from lodging between the valve 65 and the piston-stem, thereby always insuring the proper seating of the valve on the upward movement of the piston in the pump-barrel.

It will be seen that the upper end of the 70 portion of the valve immediately surrounding the piston-stem does not come in contact with the flange A', the valve being stopped in its upward movement by the depending lug A'', which engages the upper face of the valve intermediate its edges, which prevents any batter of the parts surrounding the piston-stem, thus keeping the channels E free and unobstructed.

Having described my invention, what I 80 claim as new, and desire to secure by Letters Patent, is—

1. A piston for plunger-pumps comprising a stem having a shoulder provided with downwardly-projecting lugs at the upper portion 85 thereof, said lugs having the lower portion thereof spaced apart and lying at a distance from the stem and being of a length sufficient to prevent the valve from contacting with the shoulder on the stem; a valve-seat having apertures therethrough secured to the lower portion of said stem; a valve slidably mounted on said stem intermediate the valve-seat and shoulders, and having a plurality of channels therein adjacent to the valve-stem. 90

2. A piston for plunger-pumps comprising a stem having a valve-seat secured to the bottom thereof; said seat having apertures ex-

tending therethrough; a valve slidably mounted on said stem above said seat; channels in said valve adjacent to said stem; means secured to said stem to limit the upward movement of the valve to permit the flow of liquid through said channels on and throughout the downward movement of the valve.

In witness that I claim the foregoing I have hereunto subscribed my name this 14th day of December, 1903.

PERRY J. WALLER.
